The ornamental design for tubing clips, as shown and described.

DESCRIPTION

FIG. 1 is a top, rear, right side perspective view of a tubing clip showing a new design;

FIG. 2 is a top, front, right side perspective view thereof;

FIG. 3 is a left side elevational view thereof;

FIG. 4 is a right side elevational view thereof;

FIG. 5 is a bottom view thereof;

FIG. 6 is a top view thereof;

FIG. 7 is a rear elevational view thereof; and,

FIG. 8 is a front elevational view thereof.

The broken lines are included for the purpose of illustrating the portions of the tubing clip that forms no part of the claimed design. The appearance within the unshaded areas defined by solid and/or broken lines within FIG. 8, likewise, forms no part of the claimed design.
